UNITED STATES PATENT OFFICE.

DAVID F. CURTIN, OF CHICAGO, ILLINOIS, ASSIGNOR, BY MESNE ASSIGNMENTS, TO THE VORTEX MFG. CO., OF CHICAGO, ILLINOIS, A CORPORATION OF ILLINOIS.

CONTAINER FOR PAPER CUPS.

Application filed July 3, 1922. Serial No. 572,593.

This invention relates to dispensing containers for the sort of paper cups which are usually supplied in nested form.

It is an object of this invention to provide 5 a container which shall keep the cups enclosed except at the moment of delivery.

It is a further object of this invention to provide a container which will automatically close whenever it is left to itself.

10 It is a further object of this invention to provide a container which is easily and quickly opened and in which when open, the cups are easily accessible.

It is a further object of this invention to 15 provide a container which can be made of a few parts of sheet metal so that the device shall be simple and inexpensive to manufacture.

Other and further important objects of 20 this invention will be apparent from the disclosures in the drawings and specification.

The invention (in a preferred form) is 25 illustrated in the drawings and hereinafter more fully described.

On the drawings:

Figure 1 is a front elevation.

Figure 2 is a vertical section.

Figure 3 is a side elevation.

30 Figure 4 is a top plan view.

Figure 5 is a section upon the line 5—5 of Figure 3.

Figure 6 is a section upon the line 6—6 of Figure 2.

35 Figure 7 is a broken detached view showing the operating handle.

As shown on the drawings:

The container includes a stationary semi-cylindrical holder 1 closed at the upper end 40 by a cap 2 which extends a little beyond the semi-circle so as to afford a support for a boss 3 at the upper end of the axis of the cylinder. The lower end of the cylinder is closed by a cap 4 of circular form. Both 45 the upper and the lower caps have flanges extending along the surface of the cylinder for a short distance.

Integral with the flange of the lower cap 50 is a hook 5 which is preferably secured to the cylinder wall by soldering or any other appropriate means. Secured to the same wall just below the flange of the cap 2 is a strap 6 containing a hole 7. Preferably the strap 6 is offset to pass by the cap 2 and the offset 55 is sufficient to bring the hole 7 in the same

plane with the bight of the hook 5. The hook 5 and the hole 7 in the strap 6 afford means by which the device is readily secured to any vertical support as for example to the wall.

The boss 3 carries a pivot screw 8, the head of which is milled for readiness in adjusting the same. The other end of the axis of the cylinder has a pivot 9 formed by striking up the central part of the cap 4. Preferably the struck up part has two different shaped portions of which the upper one 9 is circular, and the lower one 10 rectangular as is most clearly shown in Figure 6. Rotatably mounted upon the circular part 9 of this 65 pivot is a circular base 11 for the movable closure of the container. This base has a central hole 30 to receive the round part 9. The upper end of the closure is a semi-circular cap 12 which may have a projecting part 13 to engage the pivot at the end of the screw 8 or which may extend beyond the semi-circle in the same way as does the semi-circular cap 2.

The cylindrical part of the closure consists of a frame 15 surrounding a window 18 and secured at top and bottom to the flanges 16 and 17 respectively on the cap 12 and base 11 of the movable closure. The upper horizontal arcuate part of this frame is comparatively narrow but the lower arcuate part 25 is of considerable width and forms a substantial looking bottom below the window. The vertical portions 19 of the frame limit the window at each side thereof. The frame continues beyond the portions 19 being folded against them as shown at 20. The folded portion is offset at 21 to afford a pocket to receive the edge 22 of the flexible material 18 which constitutes the window proper. The edge 23 of the folded back portion is concealed because the offset portions 19 are wider than the folded back portions.

Secured to the base 11, coaxial with the cylinder just described is a conical supporting piece 26 which is secured in any desired way to the base 11. Projecting downward from the base 11 is a lug 27 made by striking down a portion of the base. The rectangular portion 10 of the upstruck part of the base 4 serves as an anchorage for the inner end of a spring 29 which may be soldered thereto or merely secured by being bent into the same rectangular shape as the part 10. 110

The other end of the spring 29 is bent around the lug 27 as is shown in Figure 6.

A handle 31 is integrally connected with the base 11. This handle has a vertical connecting part 32 and a radial projecting part which if desired may be curved to be more firmly contacted by the operator's finger.

In the assembly of the device the several parts described as of sheet metal are first secured together to form the stationary part and the closure separately. The spring 29 is then secured to the cup 4 by having its inner end pressed over or soldered to the rectangular part 10. The lower end of the closure is then placed approximately in the bottom of the container and the spring 29 having first been wound to the desired degree of tightness by pincers or otherwise is secured to the closure by having its outer end hooked over the lug 27. The movable closure is then brought completely into place with the central hole 30 in the base 11, fitted over the round pivot 9. The upper end of the closure will then come into place so that the hole therein will receive the pivot 14. The screw 8 is then turned until the closure is pressed against the bearing surface on the top of the rectangular part 10 with a pressure sufficient to afford the necessary degree of friction. The cups in nested form are then placed upon the conical support 26. The device is then hung upon the wall or similar support by having the hook 5 passed over a strap or staple on the wall and the hole 7 passed over the head of a screw in the wall as shown in Figure 6.

The operation is as follows:

To open the device, the operator moves the handle 31 to the right as seen in Figure 1 until it enters the notch 33 as shown in Figure 3. This rotates the closure through approximately 180° so that the cups are available and the uppermost cup may be removed. The operator may continue to push against the handle 31 during the whole of this motion or he may if desired complete the movement by pushing against the edge 20 of the frame with the back of his hand. When the

operator releases the closure either by withdrawing his hand in removing the cup or by withdrawing it without having removed a cup, the spring 29 will cause the closure to return to the position in which the handle 30 is engaged in the notch 34. The cups are then completely protected from dust or flies, and yet it requires but a single movement of the hand to make them again completely accessible.

I am aware that numerous details of construction may be varied through a wide range without departing from the principles of this invention, and I therefore do not purpose limiting the patent granted otherwise than necessitated by the prior art.

I claim as my invention:

1. In a dispensing apparatus, a bottom piece, a projection integrally formed in the center of said bottom piece, a container mounted on the bottom piece and having an opening in one side thereof, a closure for the opening, an apertured base piece for said closure rotatably engaged on said projection, a frustum shaped cup support on said base piece, and means connecting said base piece to said projection for automatically returning the closure to closed position.

2. In a dispensing apparatus, a bottom member, a struck up portion in the center of said bottom member, the struck up portion including a circular part and a rectangular part, a spring mounted upon said rectangular part, and a closure operated by said spring and mounted on said circular part.

3. In an automatically closing container, a rotatably mounted closure, a support for said closure including a circular part, a rectangular part, and a bearing surface, connecting said parts, and an adjustable pivot in line with said support whereby adjusting said adjustable pivot will regulate the pressure of said closure against the bearing surface.

In testimony whereof I have hereunto subscribed my name.

DAVID F. CURTIN.
